Inventor

UNITED STATES PATENT OFFICE

EUGENE C. TAYLOR, OF PATTERSON, LOUISIANA

ROTARY ADVERTISING APPARATUS

Application filed April 14, 1928. Serial No. 269,945.

My invention relates to apparatus for displaying advertisements of various kinds, in such a way as will be likely to attract the attention of an ordinary passerby.

It is well-known that the eye is much more quickly attracted by an object in motion than when this object is at rest, and as evidence of this, display advertisements in shop windows, where there is an element of motion involved, frequently draw crowds, where, if the same advertisement were without any movement, the ordinary passerby would go by without looking.

My invention is intended to cover not only the movement of part or all of the advertisements shown, but to impart such movement more or less irregularly, as would tend to call the special attention of the observer to same, and hold his attention for a sufficient time to impress upon his mind, imperceptibly to himself, the data borne by such advertisements.

For this purpose, I provide a rotating disk or wheel, carrying on its front face a number of advertising boards or plates, which may be in the form of disks or other shapes, and imparting to all of these advertising boards, plates or disks such motion as will be apt to rivet the attention of the ordinary bystander.

In cooperation with the wheel rotating in the vertical plane, I rotate in a horizontal plane another disk or wheel carrying advertising matter, so that an unusual variety of movements is imparted, adapted to attract the attention of the passerby, and to cause him to stop and examine the apparatus and the advertisements carried thereby.

The apparatus may be driven by any suitable source of power, such as an electric motor, belt and pulley, or cog gearing; and as such motive power is not necessarily a part of my present invention, the same will be illustrated in the conventional way, as by a pulley.

My invention will be more fully understood after reference to the accompanying drawings, in which like parts are indicated by similar reference symbols throughout the several views, and in which,

Figure 1 is a front elevation, showing the

complete advertising apparatus exclusive of the driving mechanism.

Figure 2 is a plan view of the apparatus, the motor power being illustrated as by a pulley.

Figure 3 shows a vertical section along the line 3—3 of Figure 2, and looking in the direction of the arrows.

Figure 4 is a horizontal section along the line 4—4 of Figure 3, and looking down, parts being shown in elevation.

Figure 5 shows a section along the broken line 5—5 of Figure 1, and looking in the direction of the arrows.

Figure 6 is a perspective view of one of the advertising disks, or plates, which is positively driven, as will be hereinafter described.

Figure 7 is a perspective view of one of the pivoted weighted blocks, to which the advertising matter may be attached, carried by one of the driven disks.

Figure 8 shows one of the counter-balanced disks, which is not positively driven, and tends to maintain its vertical position by gravity.

Figure 9 is a detailed view, showing the rear of one of the signs carried by the horizontal disk or wheel.

A represents a platform preferably circular in shape mounted on any suitable framework, such as the beams B, which project beyond the platform, and are connected near their ends to the upright posts B' tied together by the cross beams B².

Connected to the upper portion of these posts B' are the cross beams B³, which are mounted above and clear of the platform A. These beams B³ carry the frames C terminating in the bearing C', having the cap C², and in which bearing the main drive shaft D is journaled.

This shaft passes above another bearing C³ closed by a cap C⁴, see Figure 5, and this said shaft may be driven in any convenient way, as by the pulley E, shown in dotted lines in Figures 2 and 5.

Keyed on this outer shaft D is a wheel or disk F, which may be reinforced, if desired, with radial strips F', so as to form a better bearing surface for the stub shafts and pins that will be hereinafter described.

Arranged radially on this disk or wheel are a number of counter-balanced disks G, G' and G², having one side g^o heavier than the other, so that they will normally rest in a substantially vertical position, while the main disk F rotates.

These counter-balanced disks G, G' and G² are pivoted on pins g, g' and g², as shown most clearly in Figure 5, and advertising matter of any desired kind can be pasted or otherwise applied to the front of these disks, and this advertising matter will remain in a substantially vertical position, as the main disk rotates.

At the front end of the main shaft D, I may provide a counterbalanced disk G³ pivoted at g³ to the main shaft, and cut away as at g⁴ to throw its center of gravity below its pivot, and also to increase the attractiveness of the design.

Concentric with the shaft D is a fixed circular rack H connected by means of the screw bolts I and I' to the journal bearing C', and cap C², so that the shaft may turn, but this circular rack will be fixed. This rack meshes with the pinion J mounted on the same shaft as the advertising disk K, and this pinion J meshes with the gear J' fixed on the same disk with the advertising disk K', and the gear J' meshes in its turn with the larger gear J² on the same shaft as the advertising disk K², so that as the shaft D rotates, the fixed rack H will cause the various pinions J, J' and J² to rotate, and simultaneously will rotate the disks K, K' and K². The disks G, G' and G² and K, K' and K² are preferably arranged in radial groups, as shown.

Referring to Figure 1, it will be seen that I have shown every fourth series of advertising disks as rotating, and the other three intermediate groups of counterbalanced disks free to hang vertically on their respective pins.

Thus it will be seen that variable motion is imparted to every fourth group of advertising disks. Obviously every advertising group may be rotated, or every second or third set, if desired.

The advertisements may be applied directly to the face of the advertising disks K, K' and K², or may be connected thereto in any convenient way, as by means of the blocks M pivotally attached to the face of the disk, as by the pins m, as shown in Figures 6 and 7.

Thus it will be seen that as the shaft D rotates carrying with it the main disk F, the disks G, G' and G² will hang like pendulums, while the disks K, K' and K² will be positively driven; and thus quite a variegated effect may be imparted to the advertising media that may be disposed on the disks.

Mounted above the platform A is a horizontally disposed rotating disk N, which carries a cone bearing N' mounted on casters or rollers N², so that this disk N may be rotated

over the platform A. This disk N carries a flange P, which may be separated therefrom as by the rounded posts P', which are held in place by the screws p', and against these rounded posts, the belt Q engages. This endless belt passes over the pulley R fastened to the shaft D, see Figures 3 and 5, and then over the idlers S, and the pulleys T, see Figure 3, engaging in frictional contact with the posts P', and causing the disk N to rotate as the shaft D rotates.

Thus it will be seen that the rotation of the shaft D will not only rotate the vertical disk F, but the horizontal disk N. This horizontal disk N is also provided with advertising display arrangements, such for instance, as the card holders U, in which the advertising plates or cards V are detachably mounted.

In order to hold these cards or plates conveniently in place, the back of each may be provided with the blocks V', which fit in the holders U, as shown in Figures 4 and 9. A number of these advertising cards may be mounted on the horizontal rotary disk N.

In order to provide an element of surprise, I may mount outside the disk N and carried by the platform A, a fence-like arrangement, comprising the loops W, in which screening cards or plates X may be conveniently mounted, as shown in Figures 1 and 2. These screen cards or plates may be made of pasteboard, metal, or the like, and may bear on their faces any advertising matter; and obviously the plates may be changed from time to time.

By spacing these screen cards or plates apart, as shown in Figure 1, the advertising cards carried by the rotating disk N will be displayed seriatim, and thus we get a step by step view of the advertisements, carried by the disk N.

Obviously the loops W may be carried entirely around the platform A, as shown in Figure 4, or they may be carried through only part of the circumference of the platform. In a similar way, the screens X may be used to screen only the front or a limited portion of the apparatus, as may be desired.

Obviously these screens may be changed from time to time, or may be moved closer together or farther apart, so as to present a varied appearance from time to time.

Thus it will be seen that I have provided an advertising apparatus in which advertisements are rotated in the vertical and horizontal plane, and are partly screened from time to time, and which may be changed from time to time.

While I have referred to the blocks or plates G, G' and G² and K, K' and K² as disks, obviously they may be of any desired contour, and the term smaller disks, as used in the claims, should be so understood.

While I have described one embodiment of the invention in its preferred form it will be

obvious that various changes might be made in the construction, combination and arrangement of parts, which might be used without departing from the spirit of my invention, and I do not mean to limit the invention to such details, except as particularly pointed out in the claims.

Having thus described my invention, what I claim and desire to secure by Letters Patent of the United States is:—

1. Apparatus for advertising, comprising a main rotary shaft a vertical disk rotated thereby, a horizontal disk, means operated by said shaft for rotating said horizontal disk, means for displaying advertising matter in movable relation to said vertical disk, and means for displaying advertising matter carried by said horizontal disk.

2. Apparatus for advertising, comprising a main rotary shaft a vertical disk rotated thereby, a horizontal disk, means operated by said shaft for rotating said horizontal disk, means for displaying advertising matter in movable relation to said vertical disk, and means for displaying advertising matter carried by said horizontal disk, with means for screening off parts of said horizontal disk as it rotates.

3. Apparatus for advertising, comprising a main rotary shaft a vertical disk mounted thereon, a horizontal disk, means operated by said shaft for rotating said horizontal disk, means for displaying advertising matter on said vertical disk, and means for displaying advertising matter carried by said horizontal disk.

4. Apparatus for advertising, comprising a main rotary shaft a vertical disk mounted thereon, a horizontal disk, means operated by said shaft for rotating said horizontal disk, means for displaying advertising matter on said vertical disk, and means for displaying advertising matter carried by said horizontal disk with means for screening off parts of said horizontal disk as it rotates.

5. Apparatus for advertising, comprising a main rotary shaft, a vertical disk mounted thereon, a horizontal disk, means operated by said shaft for rotating said horizontal disk, means for displaying advertising matter in movable relation to said vertical disk, comprising a series of smaller disks pivotally mounted on said vertical disk, with gearing operated by said shaft for rotating some of said smaller disks, and means for displaying advertising matter carried by said horizontal disk.

6. Apparatus for advertising, comprising a main rotary shaft a vertical disk mounted thereon, a horizontal disk, means operated by said shaft for rotating said horizontal disk, means for displaying advertising matter in movable relation to said vertical disk, comprising a series of smaller disks pivotally mounted on said vertical disk, with gearing

operated by said shaft for rotating some of said smaller disks, and means for displaying advertising matter carried by said horizontal disk, with means for screening off parts of said horizontal disk as it rotates.
